LIQUID SOAP DISPENSING DEVICE

Ernest L. Kish, Barberton, and Maurice L. Pules,
Akron, Ohio

Application August 21, 1946, Serial No. 691,995

4 Claims. (Cl. 222—449)

1

This invention relates to a liquid soap or like dispensing device of the type adapted to be attached to a line from a source of liquid supply under pressure, gravitational or otherwise.

One object of the invention is to provide a dispenser of the type described which is relatively simple and efficient in operation, and yet which may be produced to have a minimum of parts.

Another object of the invention is to provide a liquid soap or like dispenser in which fouling of the device due to gumming up of the dispensing liquid therein is substantially obviated.

These and other objects of the invention will be manifest from the following brief description and the accompanying drawings.

Of the accompanying drawings:

Figure 1 is a plan view of a liquid soap dispenser embodying the features of the invention.

Figure 2 is a vertical cross-section taken substantially on the line 2—2 of Figure 1.

Figure 3 is a transverse cross-section, on an enlarged scale, taken on the line 3—3 of Figure 2.

Figure 4 is a similarly enlarged cross-section, taken on the line 4—4 of Figure 2.

Figure 5 is an enlarged end view from the right of Figure 2.

Referring to the drawings, the numeral 10 designates an elongated housing, of hexagonal bar or other stock and suitable material, said housing having a spring bore or cavity 11 extending longitudinally from one end to a substantial depth, and having a cylindrical passage 12 of reduced cross-section extending from the inner end of the spring cavity to communicate with a recess 13 in the opposite end of the housing. The recess 13 is internally threaded for attachment of the housing to a fixed pipe 14 which connects, for example, to a reservoir or other suitable source of liquid soap supply (not shown).

Slidably received in bore 11 is a plunger 15, including a cylindrical head 15a adapted in normal inoperative position of the plunger to have an operating portion 15b projecting freely outwardly of the end of the housing. A substantial proportional length of the plunger, extending through the spring cavity is of substantially reduced diameter and an inner end portion of this reduced portion is slidably received in the cavity end of the passage to act as a guide, and as an outlet valve part in a manner to be described later. Threaded into said inner end of the reduced portion 16 may be a screw 17 which extends coaxially through the passage 12 and terminates at the liquid receiving end of the passage in an enlarged head 18. Engaged between head

2

18 and a nut 19, threaded on the screw, may be a valve member 20 including a gasket 20a, of rubber or like sealing material, adapted to engage in sealing relation with an outwardly presented seat 21 provided at the liquid receiving end of the housing by formation of the recess 13. Nut 19 is slidably received in the end of passage 12, to act as additional guide means for the plunger in the inoperative position thereof, and thereby to assure proper seating of valve member 20. A metal washer or collar 22, between the rubber gasket 21 and head 18, provides requisite backing for stop engagement of the gasket with the valve seat. Thus, substantial length of space is provided between screw 17 and the surface of passage 12, the same defining a liquid-receiving pocket or chamber 12a which in the normal inoperative condition of the device is fully enclosed except for a liquid dispensing outlet or valve aperture 23, closely adjacent the spring-cavity end of said pocket. The parts are normally maintained in the inoperative condition described as by means of the compression spring 24, engaging between the enlarged head 15a of the plunger 15 and a rubber or like sealing gasket 25 engaged against the inner end of the spring cavity 11, gasket 25 being provided to seal that end of the passage 12 against leakage of liquid soap into the spring cavity. The aperture 23 is open when plunger 15 is in normal position, and closed by the inner end of plunger part 16 when the plunger is in yieldingly depressed position.

In the operation of the device described, when attached to the pipe 14 from a source of liquid soap, such as a supply reservoir (not shown), the soap is dispensed from outlet 23 into the cupped palm of the hand by engaging the projection portion 15b of the plunger 15 with the thumb or the heel of the hand, the plunger thereby being depressed, against the action of spring 24, to the chain-dotted line position of the plunger and associated parts illustrated in Figure 2. This plunger depressing action may be momentary and repeated as often as necessary. With each such momentary operation of the plunger it is moved so that the inner end of reduced plunger part 16 closes the outlet 23, simultaneously with opening of the valve 20, to permit flow of liquid to the pocket 12a provided in the passage 12. When the plunger is released the spring 24 actuates the plunger to close the valve 20 against its seat 21 and open the outlet 23, whereupon the liquid received in the pocket 12a is discharged through the outlet 23 into said cupped hand.

Modifications of the invention may be resorted to without departing from the spirit thereof or the scope of the appended claims.

What is claimed is:

1. A liquid soap or like dispensing device, comprising a housing having a cavity at one end thereof and a reduced passage communicating the inner end of the cavity with the opposite liquid-receiving end of the housing, means for connecting said liquid-receiving end of said housing with a source of liquid to be dispensed, a plunger mounted in said housing to have in a normal condition of the device an operating extension outwardly of the housing and having an inward extension received through said cavity and said passage, liquid-sealing means at the cavity end of said passage, a releasable liquid-sealing valve at said liquid-receiving end of said passage operable by said plunger, spring means in said cavity for yieldingly urging said plunger to said normal position in which said valve is in liquid-sealing relation to the liquid-receiving end of said passage and with said operating extension of the plunger in its said outer position, a portion of the length of said inward extension between said sealing means and said valve defining with said passage a chamber adapted to contain a quantity of said liquid, a liquid-dispensing outlet in said housing communicating said chamber with the exterior in the normal position of the plunger, means operable by said plunger in the depressed position thereof to close said dispensing outlet, said valve in the depressed position of the plunger being yieldingly released and permitting passage of liquid from said source of supply into said chamber, whereby upon release of said operating extension the plunger is yieldingly urged by said spring to close said valve and said liquid received in said chamber is discharged through said dispensing aperture.

2. A liquid soap or like dispensing device, comprising a housing having a cavity at one end thereof and a reduced passage communicating the inner end of the cavity with the opposite liquid-receiving end of the housing, means for connecting said liquid-receiving end of said housing with a source of liquid to be dispensed, a plunger mounted in said housing to have in a normal condition of the device an operating extension outwardly of the housing and having an inward extension received through said cavity and said passage, liquid-sealing means at the cavity end of said passage, a releasable liquid-sealing valve at said liquid-receiving end of said passage operable by said plunger, spring means in said cavity for yieldingly urging said plunger to said normal position in which said valve is in liquid-sealing relation to the liquid-receiving end of said passage and with said operating extension of the plunger in its said outer position, a portion of the length of said inward extension between said sealing means and said valve defining with said passage a chamber adapted to contain a predetermined quantity of said liquid, a liquid-dispensing outlet in said housing communicating said chamber with the exterior in the normal position of the plunger, a portion of said inward extension being operable in the depressed position of the plunger to close said dispensing outlet, said valve in the depressed position of the plunger being released and permitting passage of liquid from said source of supply into said chamber, whereby upon release of said operating extension the plunger is yieldingly urged by said spring to close said valve and said liquid in said chamber is discharged through said dispensing aperture.

3. A liquid soap or like dispensing device, comprising a housing having a cavity at one end thereof and a reduced passage communicating the inner end of the cavity with the opposite liquid-receiving end of the housing, means for connecting said liquid-receiving end of said housing with a source of liquid to be dispensed, a plunger mounted in said housing to have in a normal condition of the device an operating extension outwardly of the housing and having an inward extension received through said cavity and said passage, means around said plunger for liquid-sealing the cavity end of said passage, a liquid-sealing valve on said plunger extension for normally sealing said liquid-receiving end of said passage, spring means in said cavity for yieldingly urging said plunger to said normal position in which said valve is in liquid-sealing relation to the liquid receiving end of said passage and with said operating extension of the plunger in said outward position, a portion of the length of said inward extension between said sealing means and said valve defining with said passage a chamber adapted to contain a predetermined quantity of liquid, a liquid-dispensing outlet in said housing communicating said chamber with the exterior in the normal position of the plunger, a portion of said inward extension being operable in the depressed position of the plunger to close said dispensing outlet, said valve in the depressed position of the plunger being adapted to be released and permitting passage of liquid from said source of supply into said chamber, whereby upon release of said operating extension the plunger is yieldingly urged by said spring to close said valve and said liquid in said chamber is discharged through said dispensing aperture.

4. A liquid soap or like dispensing device, comprising an elongated housing having a cavity at one end thereof and a reduced passage communicating the inner end of the cavity with the opposite liquid-receiving end of the housing, means for connecting said liquid-receiving end of said housing with a source of liquid to be dispensed, a plunger mounted in said housing to have in a normal condition of the device an operating extension outwardly of the housing and having an inward extension received through said cavity and slidably in said passage, a liquid-sealing element around said plunger extension at the cavity end of said passage, a liquid-sealing valve on said plunger extension for normally sealing said liquid-receiving end of said passage, spring means in said cavity for yieldingly urging said plunger to said normal position in which said valve is in liquid-sealing relation to the liquid-receiving end of said passage and with said operating extension of the plunger in said outwardly extended position, a portion of the length of said inward extension between said sealing means and said valve being of reduced cross-section to define with said passage a chamber adapted to contain a predetermined quantity of said liquid, a liquid-dispensing outlet in said housing communicating said chamber with the exterior in the normal position of the plunger, a portion of said inward extension being engageable in said passage in the depressed position of the plunger to close said dispensing outlet, said valve in the depressed position of the plunger being adapted to be released and permitting passage of liquid from said source of supply into said chamber, whereby upon release of said operating extension the plunger is yieldingly urged by said spring to close said valve

and said liquid in said pocket is discharged through said dispensing aperture.
